(57) **CLAIM**

The ornamental design for an atomizer, as shown and described.

DESCRIPTION

FIG. 1 is a front elevational view of an atomizer showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a bottom, front and right side perspective view thereof;

FIG. 8 is a top, front and left side perspective view thereof;

FIG. 9 is an enlarged view of portion 9 in FIG. 7; and,

FIG. 10 is an enlarged view of portion 10 in FIG. 8.

The broken lines in the drawings illustrate portions of the atomizer which form no part of the claimed design.

The dot-dash broken lines surrounding the details views are for annotating the enlargements and form no part thereof.
